UNITED STATES PATENT OFFICE.

WILLIAM HENRY GARLOCK, OF SEATTLE, WASHINGTON.

DEVICE FOR PRESERVING PILES, &c.

1,033,690.

Specification of Letters Patent. Patented July 23, 1912.

Application filed November 22, 1911. Serial No. 661,884.

To all whom it may concern:

Be it known that I, WILLIAM HENRY GARLOCK, a citizen of the United States, residing at Seattle, in the county of King and State 5 of Washington, have invented certain new and useful Improvements in Devices for Preserving Piles, &c., of which the following is a specification, reference being had therein to the accompanying drawing.

10 This invention relates to the preservation of timber and has special reference to an improved manner of preserving timber and preparing the same for such preservation.

The principal object of the invention is to 15 provide means whereby a preserving fluid may be forced from the inner portion of the timber outward without splitting the same as the pressure is applied.

With the above and other objects in view 20 the invention consists in general of an improved method of preparing and preserving timber.

In the accompanying drawings like characters of reference indicate like parts in the 25 several views, and:—Figure 1 is a side elevation of the apparatus used in connection with this invention, the timber shown applied thereto being in section. Fig. 2 is an elevation of the timber with a portion of 30 the apparatus attached. Fig. 3 is a modified form of means for attaching the force pipe to a timber, the view being in section. Fig. 4 is a top plan view of the device shown in Fig. 3. Fig. 5 is a plan view of a certain 35 follower plate used herewith. Fig. 6 is a plan view of the opposite side thereof. Fig. 7 is a plan view showing the gasket used below the follower plate after compression. Fig. 8 is a section taken diametrically there- 40 through.

In preparing the timber for preservation under the method forming the subject-matter of this application the same is first bored from one end—preferably the lower 45 end of the tree—to a point somewhat remote from the opposite end of the timber, the bore being indicated at 10 in a log 11. The upper end of this bore 10 is slightly enlarged as indicated at 12. Around the 50 upper end of the timber is applied an endless metallic band 13 which prevents splitting of the upper end of the timber. Around the timber prior to applying any pressure there is wound a wire 14 which has its ends 55 secured by suitable staples 15, the wire being wound tightly so that pressure applied

within the bore 10 will not cause the timber to split, the stress being taken by the spirally wound wire. In the upper end of the bore there is then screwed a plug 16 so that a 60 union 17 may be applied thereto to connect the bore with a pipe 18 which leads from a pump 19 mounted on a tank 20 wherein is contained the preserving fluid. The pump is connected with the tank by means of a 65 suitable pipe 21. Valves 22 and 23 are interposed in the pipes 18 and 21 between their ends so that pressure may be maintained without the use of the pump 19 after the same has been raised to the required 70 point.

The form of attaching device shown in Figs. 3 to 8, inclusive, is found best adapted for certain kinds of wood wherein the preservative fluid tends to escape through the 75 end to which the nipple is applied. In this form of the invention there is provided a nipple 24 which is threaded at its lower end as is the nipple 16, and this nipple is also threaded at its upper end as at 25. The 80 pipe 18 is provided on the end adjoining the nipple with a union flange 26 and a union connecting or backing nut 27 which serves to hold the pipe and nipple closely together. Between the threaded portions of the nipple 85 24 the same is provided with a hexagonal flange 28 for the purpose of affording a grip for a wrench. Screwed on the lower end of the nipple is a follower nut 29 beneath which is a follower plate 30 which 90 has a raised annular rib 31 arranged to form a seat for the underside of the follower nut 29. The other side of this follower plate is provided with a series of concentric annular grooves 32 and the follower plate is 95 provided with a centrally disposed opening 33 of greater diameter than that part of the nipple whereon it fits so that it is free to move longitudinally thereof.

Around the follower nut are spaced 100 notches 34 for the reception of a spanner wrench so that the nut may be turned upon the nipple. Bearing against the grooved side of the follower plate is a gasket 35 of rubber or similar elastic material. The fol- 105 lower plate is made of sufficient size so as to nearly cover the head of the timber 11 and the gasket is conterminous with the fol lower plate. In using this form of the de- 110 vice the follower plate, gasket, and follower nut are placed in position on the nipple; the latter is then screwed firmly into the timber

11 and after the nipple is in position the follower nut is tightened and this results in the follower plate being forced down and the gasket being compressed and caused to enter the rings, thus preventing lateral spreading, so that it is forced firmly against the end of the timber and prevents all escape of the preservative fluid through the end pores of said timber.

10 After the parts are arranged as above described the pump 19 is operated and preservative fluid forced into the bore 10, the pump being kept going until a heavy pressure is obtained within the bore. The fluid 15 is thus forced outward through the pores of the wood and the log is kept from splitting by reason of its being wound by the wire 14.

It is to be noted that the pressure is maintained at a sufficient degree to split the log under ordinary circumstances since a high pressure is necessary to force the preservative fluid quickly from within the bore outward. Furthermore, the wire prevents 25 jury to the timber when in use such as for

piling or the like, the wire being left on after the pressure is released.

There has thus been provided a simple and efficient method of the kind set forth for preserving timber.

Having thus described the invention, what is claimed as new, is:—

In an apparatus for preserving timber, means for connecting a pressure pipe to the timber comprising a threaded nipple adapted to enter a hole in said timber; and means for preventing the escape of preservative fluid from said timber comprising an elastic gasket surrounding said nipple and lying against the end of the timber, a follower plate bearing on said gasket, and a follower nut threaded on said nipple and bearing on said plate to force the same in the direction of the timber.

In testimony whereof I hereunto affix my 45 signature in presence of two witnesses.

WILLIAM HENRY GARLOCK.
